UNITED STATES PATENT OFFICE.

LEWIS M. JENSEN, OF LA GRANDE, OREGON.

AUTOMOBILE STARTING MECHANISM.

984,432.

Specification of Letters Patent. Patented Feb. 14, 1911.

Application filed January 28, 1910. Serial No. 540,658.

To all whom it may concern:

Be it known that I, LEWIS M. JENSEN, a citizen of the United States, residing at La Grande, in the county of Union and State of Oregon, have invented new and useful Improvements in Automobile Starting Mechanism, of which the following is a specification.

The present invention provides unique mechanism for starting the engine of an automobile or like vehicle propelled by explosive engines requiring to be started by hand, the purpose being to dispense with the usual operation of cranking either in the front or at the side of the machine and to enable the operator to start the engine while seated in the machine.

The invention contemplates a cranking shaft in line with the engine shaft mounted both to rotate and to move longitudinally, a clutch having one member fixed to the engine shaft and the other to the cranking shaft, means for throwing the cranking shaft into clutched engagement with the engine shaft, and means for automatically throwing the starting mechanism out of action in the event of back-firing, whereby disastrous results are avoided.

The invention consists of the novel features, details of construction and combination of parts, which hereinafter will be more particularly set forth, illustrated in the accompanying drawings, and pointed out in the appended claim.

Referring to the drawings, forming a part of the application, Figure 1 is a front view of part of an automobile provided with starting mechanism constructed in accordance with the present invention. Fig. 2 is a side view. Fig. 3 is a detail plan view, showing more particularly the relative arrangement of the cranking and engine shafts and the parts co-operating therewith. Fig. 4 is a side view, showing the foot lever and the means whereby the cranking shaft is moved longitudinally thereby.

Corresponding and like parts are referred to in the following description, and indicated in all the views of the drawings, by the same reference characters.

The starting mechanism is shown applied to the type of machine adapted to be cranked from the front, although it is to be understood that it may be adapted to any make of machine with slight changes which will

readily suggest themselves to the skilled mechanic.

The engine shaft 1 is provided with a clutch member 2. The cranking shaft 3 is mounted in line with the engine shaft and is provided with a clutch member 4, which is adapted to co-operate with the clutch member 2 when the two shafts 1 and 3 are in engagement. The cranking shaft 3 is mounted both to have a rotary movement and a longitudinal movement imparted thereto, a rotary movement when it is required to turn the engine shaft 1, as when starting the machine, and a longitudinal movement to throw the clutch members into or out of engagement. A sprocket wheel 5 is rotatably mounted in fixed bearings and the cranking shaft 3 is mounted therein so as to turn with the sprocket wheel and to move freely therein longitudinally to admit of throwing the clutch into and out of engagement. An expandable helical spring 6 is mounted upon the cranking shaft 3 and exerts an endwise pressure thereon to normally hold the cranking shaft 3 outward and the clutch members 2 and 4 separated.

A shaft 7 is arranged transversely of the machine in advance of the engine and is provided at its inner end with an arm 8, which terminates in a fork and engages a collar 9 provided upon the cranking shaft 3. An arm 10 at the outer end of the shaft 7 is connected by means of a rod 11 with a foot lever 12 mounted upon the machine and conveniently disposed to be engaged by the foot of the operator when it is required to move the cranking shaft to bring the clutch member 4 thereof into engagement with the clutch member 2 of the engine shaft preliminary to starting the engine by cranking. Upon pressing forwardly upon the upper end of the foot lever 12 the shaft 7 is rocked in a clockwise direction so as to move the cranking shaft inward to bring it into clutched engagement with the engine shaft 1 and at the same time compressing the helical spring 6. When the engine starts the cranking shaft is thrown outward by the teeth of the clutch member 2 riding upon the teeth of the clutch member 4. When pressure is removed from the foot lever 12 the spring 6 reacts and moves the cranking shaft 3 outward, thereby disengaging the clutch member 4 from the clutch member 2.

A longitudinal shaft 13 is arranged at one

side of the machine and is provided at its front end with a sprocket wheel 14 and at its rear end with a bevel pinion 15, which is in mesh with a bevel gear wheel 16. A sprocket chain 17 connects the sprocket wheels 5 and 14 and transmits motion from the longitudinal shaft 13 to the cranking shaft 3. The bevel gear wheel 16 is provided around its periphery with a series of ratchet teeth 18, 10 which coöperate with a pawl 19 carried by an operating lever 20 arranged to extend within convenient reach of the operator of the machine when seated. The operating lever 20 is mounted in line with or upon the 15 same shaft supporting the bevel gear wheel 16 and the pawl 19 is pivotally mounted upon an extension thereof and is held in engagement with the teeth 18 by means of a spring. A bracket 21 secured to the frame 20 of the machine has a portion extending in the path of the rear end of the pawl 19 so as to engage therewith and automatically throw the pawl out of engagement with the teeth 18 in the event of the lever 20 being thrown 25 forwardly too far at its upper end. This construction and arrangement of parts prevents disastrous results in the event of the engine back-firing, because backward movement of the bevel gear wheel 16 carries the 30 lower end of the operating lever 20 rearwardly and brings the rear end of the pawl 19 in engagement with the bracket 21, with the result that the pawl is automatically disengaged from the ratchet tooth 18, thereby 35 permitting the starting mechanism to turn backward without producing any ill-effect.

When it is required to start the engine the operator seated in the machine applies pressure to the foot lever 12 so as to move the 40 shaft 3 longitudinally to bring the clutch member 4 thereof into engagement with the clutch member 2 of the engine shaft 1, after which the lever 20 is operated by an oscillatory movement, which imparts movement to 45 the bevel gear wheel 16 and to the shaft 13, said movement being imparted to the engine shaft by means of the connections herein described. The lever 20 is operated until the engine is started, the bevel gear wheel 13 be-

ing operated by means of the ratchet connection between it and the lever 20. When the engine is started pressure is removed from the foot lever 12 when the shaft 3 is moved outward by the spring 6, thereby disengaging the clutch 4 from the clutch 2. 50 55

From the foregoing description, taken in connection with the accompanying drawings, the advantages of the construction and of the method of operation will be readily apparent to those skilled in the art to which the invention appertains, and while I have described the principle of operation of the invention, together with the device which I, now consider to be the embodiment thereof, I desire to have it understood that the device shown is merely illustrative, and that such changes may be made when desired as are within the scope of the claim appended hereto. 60 65

Having thus described the invention what 70 is claimed as new, is:—

In automobile starting mechanism, the combination of a cranking shaft mounted in line with the engine shaft to receive both a rotary and a longitudinal movement, a clutch 75 comprising complementary members carried by respectively the engine and the cranking shafts, a lever under control of the operator for moving the cranking shaft to throw the same into clutched engagement with the engine shaft, a gear element rotatable with the cranking shaft and having the latter slideable therein, a power transmitting shaft connected with said gear element, a ratchet wheel geared with said power transmitting 80 shaft, an operating lever, a pawl mounted upon the operating lever and adapted to coöperate with said ratchet wheel, and means 85 for automatically disengaging the pawl from the ratchet wheel in the event of the engine back-firing or the operating lever being thrown beyond a predetermined point. 90

In testimony whereof I affix my signature in presence of two witnesses.

LEWIS M. JENSEN.
